UNITED STATES PATENT OFFICE

2,526,572

COMBINATION SMOKER'S MOUTHPIECE
AND ASH RECEPTACLE

Alexander Marshall, Portland, Oreg.

Application December 20, 1948, Serial No. 66,187

1 Claim. (Cl. 131—182)

1

This invention relates to improvements in smokers' articles, and more especially to cigarette and cigar holders.

One of the principal objects of the invention is the provision of an article of this character in which is combined a mouthpiece or holder and a receptacle for the ashes from the burned smoking material to prevent them from dropping to the floor or onto the clothing of the smoker.

Another object of the invention is the provision of a new and novel ejector built into the mouthpiece for ejecting the burned material therefrom.

Another object is the provision of an ash receptacle of this character which is of inexpensive construction, formed either by a simple punching operation or made of wire mesh or other screen material and which may be quickly and conveniently attached to the holder or mouthpiece at a minimum cost.

These and other objects will appear as my invention is more fully hereinafter described in the following specification, illustrated in the accompanying drawing and finally pointed out in the appended claim.

In the drawing:

Figure 1 is a perspective view of a combination mouthpiece and ash receptacle made in accordance with my invention.

Figure 2 is a sectional side elevation taken approximately along the line 2—2 of Figure 1.

Figure 3 is a detail view in perspective of an ejector.

Figure 4 is an enlarged sectional view taken approximately along the line 4—4 of Figure 1.

Referring now more particularly to the drawing:

The mouthpiece 1 is bored as at 2 in the direction of its length to hold a cigarette or cigar. The enlarged end of the mouthpiece is slightly reduced in diameter to form a shoulder 3A. The ash receptacle comprises a trough-shaped member 4 having an end wall 5 at one of its ends and terminating at its opposite end in ring-shaped spring fingers 6 adapted to grip the reduced diameter portion of the mouthpiece 1 for removable attachment thereto. Thus, the mouthpiece may be used with or without the ash receptacle as desired.

To stabilize the device against rolling to either side when placed upon a support I form the front wall 5 of the receptacle with a projection 6 flattened along its bottom edge as shown. At the opposite end of the receptacle I form a projection 7 also flattened along its bottom edge. These projections also elevate the ash receptacle from a support to prevent the transfer of heat from the receptacle to the support.

As a convenient means for removing a burned cigarette or the like from the mouthpiece, I pro-

2

vide an ejector generally indicated at 8 and which comprises an elongated vertical portion 9 formed with a lateral portion 10 which terminates at one of its ends in a vertical finger grip 11. The opposite end of the vertical portion 9 is coiled as shown into a cylindrical portion 12 which is slidably mounted in the bore 2 of the mouthpiece and is adapted to force the cigarette out of the bore when moved forwardly with respect to the mouthpiece. The vertical portion 9 is slidably mounted in a vertical slot 13 formed throughout the length of the enlarged portion of the mouthpiece. One side of the top of the slot 13 is offset to provide a channel 14 within which the lateral portion of the ejector is slidably mounted. The spring fingers 6 retain the lateral portion 10 within the channel 14 and the finger grip 11 prevents ejector from being accidentally removed from the mouthpiece by coming into contact with the spring piece 6 at the forward limit of its movement.

While I have shown a particular form of embodiment of my invention, I am aware that many minor changes therein will readily suggest themselves to others skilled in the art without departing from the spirit and scope of the invention. Having thus described my invention, what I claim as new and desire to protect by Letters Patent is:

An article of the class described comprising a mouthpiece bored inwardly from one of its ends to receive smoking material, said one end of the mouthpiece being slightly reduced in diameter to form an annular shoulder, said mouthpiece having a lengthwise extending slot and in open communication with said bore, an ejector comprising a cylindrical portion slidable in said bore and a body portion slidable in said slot, one end of said body portion terminating in a finger grip, an ash receptacle of trough formation terminating at one of its ends in spring fingers adapted to engage with said mouthpiece and to bear against said shoulder to form a limit stop for movement in one direction of said ejector.
